UNITED STATES PATENT OFFICE.

JAMES E. SCOVILLE, OF SYRACUSE, NEW YORK, ASSIGNOR, BY MESNE ASSIGNMENTS, OF ONE-HALF TO AUTOMATIC CARD INDEX COMPANY, OF UTICA, NEW YORK.

CARD-INDEX.

No. 835,476.

Specification of Letters Patent.

Patented Nov. 6, 1906.

Application filed September 30, 1904. Serial No. 226,724.

To all whom it may concern:

Be it known that I, JAMES E. SCOVILLE, of Syracuse, in the county of Onondaga, in the State of New York, have invented new and useful Improvements in Card-Indexes, of which the following, taken in connection with the accompanying drawings, is a full, clear, and exact description.

This invention relates to the class of indexes which comprise a holder or case in which is supported a movable set of cards on which are written memoranda to be preserved for reference.

The main object of the present invention is to produce a device of the character aforesaid, wherein the set of cards shall be normally concealed in the case and permitted to be moved independently to exposed position when required for reference, and also permitted to be independently and conveniently removed from the case to permit the desired matter to be written or printed thereon and readily replaced in the case.

Another object of the invention is to provide means which shall operate to automatically restore the cards to their normal positions. Furthermore, an object is to produce a device which shall be simple, strong, and durable in its construction, easily and conveniently manipulated for the purpose aforesaid, and which shall be neat and compact and at the same time inexpensive in its manufacture.

While the card-containing case or holder may be supported in any suitable manner, however it is more practically designed to be applied to a telephone instrument of either the so-called "desk" type or "wall" type in which the transmitter is pivotally connected thereto, preferably the former. Therefore another object of this invention is to provide simple and effectual attaching means for the case when thus applied.

To that end the invention consists in the novel construction and arrangement of the component parts of the card-index, as hereinafter fully described, and set forth in the claim.

In the accompanying drawings, Figure 1 is a front elevation of a telephone instrument of the so-called "desk" type, with a portion of the transmitter broken away and showing my card - index applied thereto.

Fig. 2 is a top plan view of the same. Fig. 3 is a detail rear view of the card-index and illustrating more clearly the means for automatically restoring the memorandum-cards to their normal or concealed positions and showing by dotted lines a card in its exposed position. Figs 4 and 5 are inner and outer end views of the card-index, respectively. Fig. 6 is an enlarged longitudinal section of the inner end portion of the case and showing the manner of uniting the end wall members of the case formed from a sheet-metal blank. Fig. 7 is a vertical transverse section on lines X X in Fig. 6. Fig. 8 is a detail view of the said blank, and Fig. 9 is a detail view of one of the memorandum-cards.

Similar characters of reference indicate corresponding parts.

A denotes the case, in which are supported the set of memorandum-cards a a. Said case is open at its top and one end and comprises a front wall b, rear wall c, bottom d, and one end wall e and is preferably formed from the sheet-metal blank A', (shown in Fig. 8 of the drawings,) as hereinafter fully explained. B denotes the standard of the well-known telephone instrument. C is the transmitter, which is adjustably mounted on a screw-threaded horizontal shaft or pin f at the upper end of the standard, which shaft is provided with the usual thumb-nut g for clamping the transmitter in its position in the well-known manner. Said case A is formed with a bracket h, by which it is attached to the telephone. This bracket is provided with a slot i, receiving the aforesaid shaft or pin f, and is clamped between the thumb-nut g and standard B, as clearly shown in Figs. 1 and 2 of the drawings. The bracket is also provided with an aperture j to accommodate the thumb-nut, as clearly shown in Fig. 1.

Across the lower outer corner of the case A extends a rigid pin k, projecting slightly at the exterior of the front and rear walls.

The aforesaid memorandum-cards a a are each provided in the bottom edge adjacent to one corner with a vertical slot l, by which slot the cards are pivotally connected to the pin k, whereby they can be tilted independently to exposed position and can be removed independently from the case when desired. Each of said cards is also provided on its top edge with an indexed tab m, projecting above

the case A. These tabs serve as thumb-pieces by which to tilt the cards to exposed position.

D represents a shelf which is pivotally supported on the projecting ends of the pin k. This shelf is normally in upright position against the outer end of the case A and is movable with the cards when the latter are tilted to exposed position, as indicated by dotted lines in Fig. 3 of the drawings. Said shelf serves as a support for the cards in said position and relieves the slotter corner portions of the cards from strain incident to such tilting. To the rear side of the shelf is rigidly fastened an arm or rod n, preferably formed with a hook or eye at its free end, to which is attached one end of a spring or rubber band o, the other end of which band is connected to the case A, as indicated at o', and clearly shown in Figs. 2 and 3 of the drawings. This spring or band o serves to move the shelf to upright position when the cards are relieved, whereby said shelf automatically restores the cards to their normal position.

I prefer to provide the case A with an additional card a², disposed back of and extending above the other cards and which may be used for various purposes, as clearly shown in Figs. 1 and 3 of the drawings. The said case may be constructed in any suitable manner. However, I prefer to form the same of the rectangular-shaped blank A', shown in Fig. 8 of the drawings, and which may be composed of any suitable kind of sheet metal.

The blank is divided by two parallel transverse dotted lines 1 1 into main side sections 2 2 and a narrow intermediate section 3, on which lines the blank is bent or deflected at right angles in like directions. By bending the blank in this manner the sections 2 2 form the front wall and rear wall, respectively, of the case, and the intermediate section 3 forms the bottom thereof. The said side sections 2 2 are subdivided by marginal dotted lines, (indicated at 4 4,) thereby pro-

ducing sections 5 5, one of which latter sections is formed with extensions 6. By bending the blank on the lines 4 4 at right angles flanges are produced which are lapped one upon the other and form the end wall. In striking up the blank slits 7 7 are made in one of the side sections parallel with and at the line 4 of folding. The other side section 5 2 of the blank is provided with U-shaped incisions 8 8 for the purpose of bending therefrom tongues 9 9, which are inserted in the aforesaid slits 7 7 of the other section and clenched on the inner face of said section, as clearly shown in Figs. 6 and 7 of the drawings. The aforesaid extension 6 of the blank is also bent on the dotted lines 10 11 and constitutes the supporting-bracket h of the case.

The slot i of the extension 6 receives the shaft or pin f of the transmitter of the telephone, and the aperture j thereof accommodates the thumb-nut g applied to said shaft.

The inner end edge of the aforesaid shelf D is adapted to engage the outer end of the case when moved to its horizontal position to limit such movement, and thus forms a stop.

What I claim as my invention is—

In combination with a card-case, formed of a single sheet of metal and comprising front and rear walls, a single end wall, a bottom, and a slotted supporting-bracket formed integral with the said end wall and extending from said end wall and having its slotted end bent at right angles to the body of the bracket, of a pin fixed in the front and rear walls and extending beyond the outer surfaces of the same, a shelf pivotally supported on the projected ends of said pin, a spring connected to said shelf and a set of memorandum-cards pivotally mounted on said pin, each card being provided on its top edge with an index-tab, substantially as described.

JAMES E. SCOVILLE.
